UNITED STATES PATENT OFFICE.

OSCAR F. HEARTWELL, JR., OF JOLIET, ILLINOIS.

BROADCAST SEED-SOWER.

SPECIFICATION forming part of Letters Patent No. 337,832, dated March 16, 1886.

Application filed September 7, 1885. Serial No. 176,362. (No model.)

To all whom it may concern:

Be it known that I, OSCAR F. HEARTWELL, Jr., a citizen of the United States of America, residing at Joliet, in the county of Will and State of Illinois, have invented certain new and useful Improvements in Broadcast Seed-Sowers, of which the following is a specification, reference being had therein to the accompanying drawings.

This invention relates to certain improvements in broadcast seed-sowers of the class designed to be attached to a farm-wagon and operated by means of power transmitted from one of the wagon-wheels as the wagon advances in the field, which improvements consist in so constructing the parts as to render them capable of being vertically adjusted on the wagon, and in the construction and arrangement of the parts in the bottom of the hopper and in the distributor, and is intended as an improvement on the seed-sower described in Letters Patent of the United States, No. 319,411, dated June 2, 1885, granted to applicant.

Referring to said drawings, making a part of this specification, Figure 1 is a side view of the rear part of a wagon having a seed-sower attached to it as it would appear in service, and having a portion of the wagon-bed broken away to more clearly show the manner of attaching the seed-sower to a wagon. Fig. 2 is a top view of the seed-distributer. Fig. 3 is a rear view of a seed-sower, showing it attached to a wagon-bed. Fig. 4 is a cross-sectional view of one of the arms of the seed-distributer. Fig. 5 is a detailed view of the parts of the seeder, which are arranged at the base of the hopper to gage the quantity of seed to be sown and to regulate the delivery of seed on the distributer, portions being broken away to more clearly show their arrangement. Fig. 6 is a top plan view of a bed-plate, upon which the adjustable parts at the base of the hopper are arranged. Fig. 7 is a view of said bed-plate, looking at it from the front part of the seed-sower. Fig. 8 is a central vertical cross-section of the parts of the seed-sower located at the base of the hopper. Fig. 9 is a side view of one pair of the vertical slides and their parts which attach a seed-sower to a wagon. Fig. 10 is a bottom plan view of the partially-

rotating plate located in the bottom of the hopper, and which has flanges arranged on it to form a guideway for the cut-off slides and for the seed-gage slide, so that said slides may be constantly held in the same relative position with said plate. Fig. 11 is a cross-sectional view of a pair of the vertical slides for attaching the seed-sower to a wagon to show their engaging-surfaces; and Fig. 12 is a plan view of one of the cut-off slides of the seed-sower.

A represents a wagon-bed, and has attached to its rear end a seed-sower in such manner as to be operated, as the wagon advances, by a sprocket-chain, S³, (see Fig. 1,) passing over sprocket-wheel S, which is clipped to the wagon-wheel, and sprocket-wheel S' of the seeder, which sprocket-wheel is adjustably secured on the horizontal shaft S², (see Fig. 3,) which is supported in bearings secured to the frame of the seeder, and which bears the large bevel gear-wheel C.

B' is the base-board of the seeder, and has secured to its front part a board, B, arranged to extend down at right angles with said base, and together with said base forms the body or frame of the seeder.

To the upper face of base-board B' is arranged the necessary parts for gaging and delivering the seed to the distributer, and the hopper for holding the seed to be sown, and said base-board, together with said parts, forms a bearing for the upper end of perpendicular shaft Z, (see Figs. 3, 5, and 8,) which extends up into the hopper and has fixed in it a horizontal pin arranged to project in opposite directions out over the seed-delivering apertures, and is for the purpose of agitating the seed as it is rotated, to insure positive delivery, and is also arranged to extend below said base-board and rest in a step-box, and has fixed on it the seed-distributer D, immediately under said base and under the apertures in the parts at the bottom of the hopper, and a bevel-pinion, m, so arranged as to mesh with the bevel gear-wheel C and be rotated thereby.

The parts designed to hold sheave-wheel a² in contact with chain S³ are shown in Figs. 1 and 3, and consist of a bar, a, secured to the frame of the seeder, and arranged to project at one side under the sprocket-chain. On this bar an arm, a', which bears on its outer end

the sheave - wheel a^2 , and a coil - spring, w , placed on said bar and secured at its inner end to prevent rotation, while its outer end hooks under arm a' to hold it up, so wheel a^2 will 5 engage and be firmly held against the chain by tension given said spring, of a collar placed on bar a , (shown at a^4 , Fig. 3,) which serves to hold arm a' at any particular place on the extending part of bar a .

10 The vertical slides for attaching a seeder to a wagon are shown in Figs. 1, 3, 9, and 11, and consist of a pair of guiding-bars, $d d$, having hooks h at their upper ends for hooking over the end-gate of a wagon, and offsets for 15 resting on the rear end of the floor of the wagon bed, and a short distance below said offsets are arranged screw-threaded swivels v , which receive the screw-hooks v' , for the purpose of securing the lower part of said guiding-bars to the rear cross-bar of the under part of the wagon-bed, as shown in Fig. 1, and of a pair of slides, $d' d'$, attached to the seeder-frame, which are arranged to be bolted to the guiding-bars $d d$ by bolts $t t$ in such manner 20 that said bolts will, when the seeder is adjusted vertically, traverse the slots M of bars $d d$. (See Fig. 9.) The engaging-surfaces of these guiding-bars and slides are corrugated lengthwise, (see Fig. 11,) so they may not become 25 misplaced, and so they will have greater frictional contact with each other when the bolts are tightened to hold the seeder at the desired height.

The parts for gaging and regulating the delivery of seed are shown in Figs. 5, 6, 7, 8, and 10, and consist of a bed-plate, K , having extending side lugs, a pair of elongated apertures, $n n$, a central perforation for shaft Z , and a depression, o , in its front part, which has a 35 front slotted portion, o' , (see Fig. 6,) of a partially-rotating plate, E , having a pair of seed-delivering apertures, g , a central perforation for shaft Z , a forward-projecting portion, E' , and extending bottom flanges, R , arranged in such manner as to form a rectangular space between their walls, and arranged 40 to rest upon bed-plate K ; of a rim, F , having a large central opening and provided with an offset on its inner edge, as shown in 45 Fig. 8, to receive the periphery of plate E , and having a downwardly-extending flange on its outer edge, excepting the space occupied by the extending portion E' of plate E , arranged to rest on base-board B' , to inclose the 50 parts. The under part of said rim has bosses f (see Fig. 8) arranged to rest upon the side lugs of bed-plate K , so the parts are held to the base-board B' by the bolts y , passing through both parts K and E , and of the cut-off slides 55 $J J$, which have apertures T , and the seed-gage slide G having apertures $X X$, near its inner end and an index-scale on its outer end.

The hopper H is secured to a bottom flange in the ordinary manner, and rests and is secured upon rim F by means of the bolts y .

The arrangement of the adjustable parts

at the base of the hopper is as follows: The bed-plate K rests on the upper surface of base-board B' , and upon this bed-plate rests the downwardly-extending flanges of the plate E in such manner as to form a rectangular chamber between said bed-plate and plate E and the walls of said flanges. In this chamber the cut-off slides $J J$ and seed-gage slide G are placed so their apertures will correspond with the apertures in plates K and E when it is desired to sow seed; but when seed is not being sown the cut-off slides are pushed in so their apertures will pass the other apertures and cut off the discharge of seed.

80 Either slide J may be used separate from the other to cut-off the discharge of seed from its side, so the seeder will only sow seed at one side and one way from the wagon.

The seed-gage slide G has attached to its under side a depending eye-lug, L , which extends down between the cut-off slides $J J$ and into the depressed portion O of plate K , and a thumb-screw, P , arranged through slot o' in the front part of plate K , and screwed into 90 said eye-lug, and is for the purpose of moving said gage longitudinally by turning the thumb-screw, and be retained at any desired place by said screw, to regulate the quantity of seed to be sown to the acre by shifting the apertures 95 of the gage to diminish or increase the passage of seed from the hopper so the seeder may be adapted to sow different kinds and quantities of seed.

The portion E' of plate E extends at the 100 front part of the seeder at the base of the hopper from under rim F far enough so it may be moved in either direction to partially rotate plate E and the slides and gage below it, so the aperture at one side will be as much or as little 105 one in advance of the other as required for the purpose before stated, and the plate E be held when adjusted by thumb-screw b , which is arranged in rim F so it can be turned against E' .

The apertures in plate K are elongated so 110 seed may pass through them freely (the base-board being cut away below them) from the apertures above them, wherever it is required to set the apertures of plate E .

The cut-off slides J are cut away on one 115 side, as shown in Fig. 12, to give room for the depending eye-lug L .

The seed-distributer D on shaft Z , which rotates to scatter seed that is delivered upon it, has its four radial arms slightly curved forward at their outer end, as shown in Fig. 2, and to their upper part is formed forwardly-projecting flanges (shown at D' , see Fig. 4,) to prevent seed from being thrown too high.

Having thus described my invention, what 125 I claim as new and useful, and desire to secure by Letters Patent, is as follows, to wit:

1. In a broadcast seed-sower, the vertical guiding-bars d , having the attachments, substantially as shown and described, for securing 130 them to a wagon-bed, in combination with the slides d' , secured to the frame of the seeder,

and the means, substantially as set forth, for uniting said parts to hold the seed-sower adjusted vertically, for the purpose specified.

2. In a broadcast seed-sower, the means described and shown for giving vertical adjustment, consisting of the combination of the guiding-bars d , having hooks h , and swivels v , and screw-hooks v' , for attaching them to a wagon-bed, slides d' , secured to the seeder-frame, and bolts t , constructed and arranged substantially as set forth.

3. In the broadcast seed-sower described, the seed-distributer D , having its extending radial arms slightly curved forward at their outer end, and having forwardly-extending flanges arranged on the upper part of said radial arms, as and for the purpose set forth.

4. In combination with the chain and chain-wheels for operating the seed-sower, and the means for holding tight said chain, consisting of the bar a , arm a' , sheave a'' , and spring w , a seed-sowing machine arranged to be vertically adjusted, substantially as and for the purpose set forth.

5. In the seeding-machine shown and described, and in combination with the stationary base-plate K , constructed as specified, and the rim F , the rotatable plate E , having the flanges R , separate apertures $g g$, and extension E' , gage-plate G , having the separate apertures X X , and slides $J J$, each having an aperture, r , substantially as and for the purpose set forth.

6. In combination with the frame of the seed-sower arranged to be vertically adjusted, as specified, the hopper H , the flanged rim F , the bed-plate K , having the two independent elongated apertures $n n$, depression o , and slotted face-flange o' , plate E , arranged to be partially rotated, and having the two independent apertures $g g$, flanges $R R$, and extension E' , the slides $J J$, each having an aperture, r , gage-plate G , having the two independent apertures $X X$, depending lug L , and thumb-screw P , the shaft Z , the distributer D , the bevel-gears m and C , and the means shown and described for operating said parts, as and for the purpose set forth. 35 40 45

7. In combination with the frame of a seed-sowing machine and the hopper thereof, the cast stationary base-plate K , flanged rim F , rotatable plate E , seed-gage plate G , and cut-off slides $J J$, arranged above the upper surface of the seeder-frame, and having two separate and distinct seed-discharging ports arranged in advance, and one at either side of the distributer-shaft Z , and arranged to bring one of said ports in advance of the other by means of rotating said plate E , as and for the purpose set forth. 50 55
